UNITED STATES PATENT OFFICE.

PETER CORNELIUS FORRESTER, OF STEILACOOM, WASHINGTON.

MATCH-MACHINE.

1,051,571.

Specification of Letters Patent. Patented Jan. 28, 1913.

Application filed January 16, 1911. Serial No. 602,777.

To all whom it may concern:

Be it known that I, PETER C. FORRESTER, a citizen of the United States, residing at Steilacoom, in the county of Pierce and 5 State of Washington, have invented a certain new and useful Improvement in Match-Machines, of which the following is a specification.

My invention relates to improvements in 10 match making machines and is illustrated diagrammatically in one form in the accompanying drawings, wherein;

Figure 1 is a rear elevation; Fig. 2, a plan view, in part section along the line 2—2 of 15 Fig. 1; Fig. 3, a section along the line 3—3 of Fig. 2; Fig. 4, a section along the line 4—4 of Fig. 2; Fig. 5, a side elevation of veneer case with parts broken away; Fig. 6, a front elevation of veneer case; Fig. 7, a 20 side elevation of the splint case in part section; Fig. 8, a front elevation of the splint case; Fig. 9, a perspective view of a veneer strip.

Like parts are indicated by like letters 25 throughout the several figures.

The frame A supports the bearings A¹ in which rotate the shaft A² driven by the pulley A³ and carrying at either end the crank disks A⁴. The connecting rods A⁵ are 30 carried by the disks A⁴ and drive the vertical reciprocating knife bars A⁶, which carry the knives A⁷. The knives A⁷ which are in the plane of the knife bars A⁶ and project outwardly on either side thereof, are provided with the two beveled cutting edges A⁸ 35 and the projecting lugs A⁹ which are located on the side of the blade near either end thereof and the projecting lugs A¹⁰ which are located on the same side of the blade and 40 at either side of the knife bar and may have surfaces in continuation with said beveled edges.

The anvil block B is located in the plane of the knife bars and is provided with the 45 vertical slot B¹ so shaped as to permit the passage of the knife, and provided with the parallel horizontal slots B² at right angles with the motion of the knife. The veneer cases C which are made up of the rigid, 50 grooved, spaced side plates C¹, the rigid bottom plate C² and the perforated end plate C³, are rigidly held upon the frame A in opposition to the anvil block B in such manner that the slots C⁴ in the side plates 55 C¹ register with the slots B². The false end C⁵ is slidably held within the case C in a

plane parallel with the plane of the knife bars A⁶. The splint cases D which are made up of the rigid top D¹, bottom D² and end D³ contain the spaced, flexible parallel 60 spring loop fingers D⁴ supported in the end D³ and are rigidly held on the frame A in opposition to the anvil block B in such manner that the spaces between the fingers D⁴ register with the horizontal slots B² in the 65 anvil block B. The lead screw E is rotatably mounted on the frame A and carries at one end the driving head or disk E¹ which has the four outwardly projecting fingers E² in opposition to the spring held 70 pawls E³, E⁴, which are carried respectively on the arms E⁵, E⁶ on the cross bar E⁷, which in turn is mounted on the knife bars A⁶. The split nut E⁸ is in opposition to the lead screw E and carries the cross bars E⁹ 75 riding on the guides E¹⁰ and carrying the rigid, horizontal plungers E¹¹ which are adapted to enter the perforations in the back of the veneer case and engage the false end C⁵. The veneer strips F are located 80 within the veneer case, each being carried in one of the slots and the match splints are held within the splint case between the adjacent spring loop fingers D⁴.

It will be evident that while I have shown 85 in my drawing an operative device, still numerous changes might be made in size, shape and arrangement of the parts, parts might be omitted or other parts substituted or both, changes in proportions or in arrangements might be made without departing materially from the spirit of my invention, and I wish therefore, that my drawings be regarded as in a sense diagrammatic.

The use and operation of my invention are 95 as follows: The veneer cases are first filled with flat veneer strips of the thickness equal to the thickness of the match and the width equal to the length of the match, one veneer strip being placed in each slot of the veneer 100 case. The veneer cases are then placed on a machine in opposition to the anvil block. The plungers are brought up into engagement with the false end, the split nut is clamped about the lead screw and the machine is started. The knife reciprocates 105 back and forth in a direction perpendicular to the veneer strips. Starting in the position shown in Fig. 1 the knives will descend and the upper pawl will catch one of the 110 fingers on the driving head of the lead screw at the end of its descent, and give it a quar-

ter turn. When the knife starts back, the lower pawl will catch a finger on the other side and give it a quarter turn. Thus for every single reciprocation of the knife, the 5 lead screw gets a quarter turn and this turning effect takes place after the knife has passed out of the anvil block. The lead screw may be so designed that this quarter turn is sufficient to force the split nut forward carrying with it the false ends and veneers a distance equal to the width of the match. This process continues until the veneer has been forced through the anvil block and enters the plane of the knife. 10 15 The knife will then, with every reciprocation cut off a splint from the end of each of the veneer strips, this splint being the desired thickness of the match. The lugs on the side of the knife blade will force 20 25 the match splint into the other side of the anvil block and the next movement of the knife will cut another splint and force it in, thus forcing a second splint into the anvil block and forcing the first one farther along. This process will continue until the 30 35 veneer strips have been entirely cut up into match splints and until the movement of the lugs on the knife blade has forced all the match splints into the splint cases, which 30 have meanwhile been placed in opposition to the anvil block in such manner that the square match splints are forced from the block into the space between the spring fingers. The empty veneer cases and the 35 40 loaded splint cases may then be removed and have substituted for them loaded veneer cases and empty splint cases, and this process may continue without interruption of the operation of the machine. It will thus be seen that the knife or cutting means for slicing off the splints from the end of the veneer also acts to force the splints into the splint cases. It will also be seen that the movement of the wood from the time it 45 50 enters the machine as a veneer in the veneer case until it leaves it as a splint in the splint case is in the same direction, that I provide one device for both cutting off the splints and loading the splint cases. It will be observed also that one stroke of the knife 55 60 operates to cut off a splint from each of a large number of veneer cases and that the number of matches which may be produced by one stroke of the knife is limited only 65 70 by the number of veneer strips which may be placed in the path of the moving knife. It will moreover be observed that I provide means for turning the lead screw to advance the veneers, this means being operative only after the knife has passed 75 80 through the cutting zone and before it returns to it. The result of this arrangement is that there is no mutilation of the splints and that the splints are all of the same thickness and there is no binding of the knife, 85 90 95 100 105 110 115 120 125 130

owing to the movement of the veneers while the splints are being cut.

In my specification and claims, I have used the term "splint cases." It will be understood that by this term I mean what are usually called splint dipping frames or trays. I prefer, however, to use the shorter term since it will instantly be obvious that this term is adequately descriptive of these devices, and it will be understood that these splint cases are so disposed with relation to the shear block that the cut splints are fed from the block into this splint case in such number as to ultimately fill the splint case, whereupon the case may be removed from the machine, the match splints staggered and then dipped in any suitable manner.

I claim:—

1. In a match-making machine a splint case comprising a frame member and fingers projecting therefrom and substantially parallel to each other and free at their outer ends to admit of the entrance of the splints sidewise between them and projecting out from the frame a sufficient distance to accommodate a row of splints arranged side by side.

2. In a match-making machine a splint case comprising a frame member with a series of projecting fingers of unequal diameter and arranged so that their long diameters lie in a series of parallel planes separated from each other by a distance substantially equal to the diameter of the splint, said fingers free at their outer ends to permit the introduction of the splints sidewise between them and projecting out from the frame a sufficient distance to accommodate a row of splints arranged side by side.

3. In a match-making machine a splint case comprising a frame member and loop fingers projecting therefrom at a substantially equal distance from each other and free at their outer ends to permit the introduction of the splints sidewise between them and projecting out from the frame a sufficient distance to accommodate a row of splints arranged side by side, both arms of each loop being located in a plane parallel with the plane containing the arms of each other loop.

4. In a match-making machine a veneer case comprising side members with opposed parallel grooves in which the veneers can be supported in a separated condition and a plunger adapted to pass between such grooves and means for pressing same forward to force the veneers along the grooves, a block with chambers parallel with and in alignment with the grooves to receive the veneers and slotted at right angles thereto, a cutting knife and means for operating same through the slot and a splint case on the op-

- posite side of the block comprising a series of fingers in alinement with the veneer slots their ends supported in proximity to the block so that the splints can be driven thereinto sidewise.
5. In a match-making machine comprising a perforated shear block, said perforations horizontally disposed, a knife and means for horizontally reciprocating said 10 knife perpendicular to said slots, a removable splint case having splint holding means in register with said perforations.
6. In a match-making machine comprising a perforated shear block, said perforations horizontally disposed, a knife and means for horizontally reciprocating said 15 knife perpendicular to said slots, a veneer case containing veneer strips and a splint case having splint holding means in register 20 with the said perforations.
7. In a match-making machine comprising a perforated shear block, said perforations horizontally disposed, a knife and means for horizontally reciprocating said 25 knife perpendicular to said slots, a veneer case containing veneer strips and a splint case having splint holding means in register with the said perforations, means for feeding 30 veneer strips from the cases through the perforations in the anvil block.
8. In a match-making machine comprising a perforated shear block, said perforations horizontally disposed, a knife and means for horizontally reciprocating said 35 knife perpendicular to said slots, a veneer case containing veneer strips and a splint case having splint holding means in register with the said perforations, means for feeding 40 veneer strips from the cases through the perforations in the anvil block, said means responsive to the motion of the knife.
9. In a match-making machine comprising a perforated shear block, said perforations horizontally disposed, a knife and means for horizontally reciprocating said 45 knife perpendicular to said slots, a veneer case containing veneer strips and a splint case having splint holding means in register with the said perforations, means for feeding 50 veneer strips from the cases through the perforations in the anvil block, said means responsive to the motion of the knife and operative only when the knife has progressed beyond the anvil block.
55. 10. A match-making machine comprising a perforated shear block having horizontally disposed perforations, a knife, and means for horizontally reciprocating said knife perpendicular to said perforations, a veneer case
- containing veneer strips and a splint case 60 having splint holding means in register with the said perforations and means for feeding splints from the anvil block into the splint cases.
11. A match-making machine comprising a perforated shear block having horizontally 65 disposed perforations, a knife, means for horizontally reciprocating said knife perpendicular to said perforations, a veneer case containing veneer strips and a splint case 70 having splint holding means in register with the said perforations and means for feeding veneer strips to the anvil block and means for feeding splints from the block to the splint cases.
12. A match-making machine comprising a channel block to receive the veneers, means for feeding the veneers through such channel, a transversely operating knife to cut the splints from the veneers, a splint case in 80 proximity to the block with splint receiving fingers and means carried by the knife for successively feeding forward the severed splints between the fingers of the splint case and packing them in parallel rows in the 85 splint case.
13. A match-making machine comprising a channel block to receive the veneers, means for feeding the veneers through such channel, a transversely operating knife to cut the 90 splints from the veneers, a splint case in proximity to the block with splint receiving fingers and means associated with the knife for successively feeding forward the severed splints between the fingers of the splint case, 95 said block provided with a transverse channel in which the knife operates.
14. In a match-making machine a slotted shear block, a knife reciprocating through said block at right angles to said slots, a removable splint case in opposition to said 100 block and means directly responsive to the movement of the knife for forcing splints from said anvil block into said splint case.
15. In a match-making machine a slotted shear block, a knife reciprocating through said block at right angles to said slots, a removable splint case in opposition to said 105 block and means directly responsive to the movement of the knife for forcing splints from said anvil block into said splint case, and means comprising a veneer case for feeding veneers through the slots in said anvil block to the knife.
